US0D1051877S

(12) **United States Design Patent** (10) **Patent No.:** **US D1,051,877 S**
(45) **Date of Patent:** **** Nov. 19, 2024**

(54) **REMOTE CONTROL**

(71) Applicant: **SIGNIFY HOLDING B.V.**, Eindhoven (NL)

(72) Inventor: **Wessel Peter Deurwaarder**, Eindhoven (NL)

(73) Assignee: **SIGNIFY HOLDING B.V.**, Eindhoven (NL)

(**) Term: **15 Years**

(21) Appl. No.: **29/850,885**

(22) Filed: **Aug. 24, 2022**

(30) **Foreign Application Priority Data**

Feb. 25, 2022 (EM) 008869382-0001

(51) **LOC (14) Cl.** **14-03**

(52) **U.S. Cl.**

USPC **D14/218**

(58) **Field of Classification Search**

(57) **CLAIM**

The ornamental design for a "remote control" as shown and described.

DESCRIPTION

FIG. 1 is a perspective view showing my design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The portions of the remote control depicted in broken lines form no part of the claimed design.

1 Claim, 4 Drawing Sheets
